UNITED STATES PATENT OFFICE.

FRANK B. COMINS, OF SHARON, MASSACHUSETTS.

MOISTENING-MACHINE.

1,110,746.

Specification of Letters Patent. Patented Sept. 15, 1914.

Application filed June 6, 1912. Serial No. 702,061.

To all whom it may concern:

Be it known that I, FRANK B. COMINS, of Sharon, in the county of Norfolk and State of Massachusetts, have invented certain new and useful Improvements in Moistening-Machines, of which the following is a specification, reference being had to the accompanying drawings, forming part thereof.

10 This invention has reference to improvements in machines for moistening the undertip or vamp portions of shoe uppers and the lining and reinforce material thereof.

One object of the invention is to so construct a moistening machine of this nature that the moistening spray may be directed to and confined about the undertip or vamp portion of the lasted or partially lasted shoe upper whereby the linings and reinforce material may be dampened to facilitate the stretching of said portions of the shoe during the subsequent lasting, pulling over or other processes.

Another object of the invention is to so construct a moistening machine of this nature that the application of moisture to portions of the shoe in process of operation may be facilitated.

Another object of the invention is to so construct a moistening machine of this nature that the placing of the partially lasted shoe in position may effect the operation of the moisture delivering mechanism.

Other objects of the invention will appear from the following description.

The invention consists in the means for confining the undertip or toe portion of a lasted or partially lasted shoe, and means for controlling the application of moisture thereagainst.

The invention also consists in the means for automatically controlling the moisture delivering mechanism.

The invention also consists in such other novel features of construction and combination of parts as shall hereinafter be more fully described and pointed out in the claims.

Figure 1 represents a view in elevation of the improved moistening machine. Fig. 2 represents a plan view of one of the frames for supporting the partially lasted shoe upper and for confining the tip or toe portion thereof, the position of said shoe upper, when under operation in this machine being indicated. Fig. 3 represents a vertical sectional

view of the moistening machine taken on line 3—3, Fig. 1, looking in the direction indicated by the arrow of said line, the partially lasted shoe upper being shown in position. Fig. 4 represents a perspective view of the controlling lever by which the inlet valve of the air supply is operated.

Similar numbers of reference designate corresponding parts throughout.

Vamp portions of the shoe upper at the toe usually comprise an outer layer, a lining of textile material, and reinforce or strengthening layers of textile material located between said lining and said outer layer, such outer layer being usually of leather or other suitable material. In order to satisfactorily last the shoe upper, it is essential that these various layers of material be drawn tightly and smoothly over the toe portion of the last and stretched to some extent. In order to facilitate the stretching, the shoe upper has been placed on the last and the raw under portions of said material have been drawn over the sole portion of the last and secured by tacks. These partially lasted shoe uppers are then placed in steam chambers to which steam has been supplied to moisten the material forming the toe portions of the shoe. Objection has been raised to this method of moistening said portions of the shoe upper as it is not possible to limit the application of moisture to the particular part of the shoe upper, and that the heat of the steam is apt to injure the leather, and that the reduction in temperature of the moisture when the article is removed from the steam chamber tends to effect the rapid drying of the parts.

In carrying my invention into practice it has been my object to apply moisture to the partially lasted shoe upper at or about the temperature of the atmosphere and to localize the application of said moisture to those portions only of the lining, reinforce or upper layer of the shoe vamp particularly under consideration. In its preferred form I have herein shown the moisture applying device in connection with a suitable water tank and it is to be understood that this water tank represents any well known means for supplying moisture to an atomizer or other suitable moisture delivering device, whether said moisture is delivered thereby as a spray or as a jet.

As shown in the drawings, 5 represents a water tank having the supply pipe 6 through

which the inflow of water is controlled by any ordinary and well known float operated valve, indicated as a whole by the numeral 7. The cover 8 is hinged to the tank 5 and has one or more openings in each of which is mounted the fore part of the frame 9 having the general shape shown in Fig. 2 and furnished at its forward end with the concave toe receptacle 10 and at its sides upwardly and outwardly extending members 11, 11 connected by the rod 12 and at its rear portions with the upward extending arms 13, 13 connected by the cross rod 14 and by the upper cross member 15. Mounted in the forward portion of frame 9 is the deflector plate 16 having a tongue 17 extending toward the cap 10 and of the general shape shown in Fig. 2 whereby the slot or opening 18 is formed between said tongue 17 and the wall of the frame 9 adjacent the cap 10.

Mounted in one wall of the tank 5 is the atomizer 19 of any usual construction adapted to effect the atomization of moisture supplied thereto by or through the flow of air under pressure through said atomizer, said atomizer being so positioned and directed that the atomized moisture supplied therefrom will be directed into the atomizer chamber formed beneath the deflector 16 so that the natural flow of said atomized moisture will be through the slot or opening 18.

In order to facilitate the supply of air to the atomizer 19 I provide the air supply pipe 20 having as many branches 21 as there are atomizers. These pipes are furnished with valves as 22 indicated in Fig. 3 which are adapted to be closed by the air pressure passing through their valve chambers. Mounted on the valve chamber of said valve 22 are the standards 23, 23 to which are pivotally connected the levers 24 bent upward at their forward ends and having the plates 25. These levers 24 are engaged with the rods 26 which bear against the stems 22' of the valves 22 so that by pressing downward the plate 25 rod 26 may effect the opening of the valve 22 against the air pressure in said valve chamber.

When it is desired to operate this moistening machine to moisten the undertoe portion of a shoe vamp the partially lasted shoe A is placed in the machine as shown in Fig. 3, the toe portion B thereof being located in the receptacle 10 with the raw edge C of the outer layer, lining and reinforce materials extending into the channel 18 between the tongue 17 of the deflector 16 and the frame 9 adjacent to the receptacle 10. In such position the weight of the shoe and its last is sufficient to depress lever 24, by bearing against the plate 25, until the heel portion of the last or some portion of the shoe upper is sustained by the cross member 15. The depression of lever 24 operates rod 26 which

effects the depression of valve 22 against the air pressure in the air supply pipes or branches 21. The air then passes through the chamber of valve 22 into and through the atomizer 19 effecting the drawing of moisture from the tank 5 and the atomization of said moisture so that the spray from said atomizer passes forward against the deflector plate 16 to the forward portion of frame 9 and through the slot 18 to the raw edges of said lining and reinforce material of the shoe vamp whereby such material located adjacent the toe portion of the vamp is moistened to any desired extent depending upon the amount of moisture delivered thereto or the duration of the operation. After a suitable time has elapsed the partially lasted shoe upper with its last is removed and the upward movement of lever 24 is permitted thereby under the pressure of the air acting on valve 22.

Atomizer 19 may be and preferably is provided with the valve 19' whereby the flow of air through the atomizer may be controlled.

It is to be understood that, under some conditions, a water jet or steam nozzle may be substituted for the atomizer without departing from the spirit of this invention the main object of which is to supply moisture in some form to the undertoe portion of the partially lasted shoe.

Having thus described my invention I claim as new and desire to secure by Letters Patent—

1. A moistening machine of the nature described comprising atomizing means, a spray receiving chamber having a receptacle arranged to receive the toe portion of a shoe, and means for deflecting said spray toward the undertoe portion of a partially lasted shoe located in said receptacle. 100

2. A moistening machine of the nature described comprising an atomizer, means for sustaining a partially lasted shoe adjacent to said atomizer and means for guiding the atomized moisture to the toe portion of said shoe. 110

3. A moistening machine of the nature described comprising a frame, a deflector mounted on said frame and provided with a tongue, a receptacle extending above said tongue and arranged to receive the toe portion of a partially lasted shoe, and means for directing moisture toward said deflector. 115

4. A moistening machine of the nature described comprising a water supply, an atomizer coöperating therewith, and a frame mounted adjacent said atomizer and having means adapted to receive the toe portion of a partially lasted shoe, said sustaining means 120 having a slot through which portions of the material of said shoe may extend.

5. A moistening machine of the nature described comprising a water chamber having an opening in its top, a shoe supporting 130

frame mounted above said opening and having a deflector, an atomizer mounted on said water chamber and having a valve and a pressure supply pipe, a pivoted lever adapted to be moved by the weight of a partially lasted shoe, and means operated by the movement of said lever for operating said atomizer valve.

6. A moistening machine of the nature described comprising a water chamber having a curved opening in its top, a shoe toe re-

ceiving receptacle extending above said opening whereby the unlasted portion of a shoe upper may extend through said opening into said chamber, an atomizer mounted 15 on said chamber for directing spray toward said opening, and means for controlling the supply of moisture to said atomizer.
